ADJUSTABLE COUNTER-WEIGHT

Harry C. Jones, New York, N. Y.

Application March 28, 1932, Serial No. 601,673

16 Claims. (Cl. 95—73)

This invention relates to improvements in counter-weighted structures and more particularly to photo-printing frames and stands in which one or more frames are inclinable from a horizontal position, or spacedly separated.

One of the objects of this invention is to provide a fixed stand on which is pivotably mounted a frame having a second, superposed frame so connected as to be retained in registration and provided with means for causing angular or vertical separation.

A further feature is in the provision of a novel system of counter-weights for the upper frame, means for adjusting the counter-weight at various distances whereby an accurate balance may be obtained, and means for retaining the counter-weight in any desired adjustment.

A further purpose is to produce means for increasing or decreasing the gravity effect of the counter-weight by the application of variables thereto.

A still further feature resides in the means for latching the frames together or to the stand.

These and other important features are attained by the novel and practical construction, combination and arrangement of parts herein-after described and shown in the accompanying drawings, in which:

Figure 1 is a side elevational view of an embodiment of the invention shown in closed position.

Figure 2 is a top plan view of the rear portion of a geared embodiment of the same.

Figure 3 is a partial side elevational view of the upper portion of a modified form of the device.

Figure 4 is a similar view showing a further modification of the same.

Figure 5 is a side elevational view of the upper portion of a different type of the device.

Figure 6 is a similar view showing a modified form of clamping means.

Figure 7 is a side elevational view showing the rear portion of the machine as provided with a modified form of weight adjusting means.

Figure 8 is a similar view of a further modification.

Figure 9 is a front view of the machine, showing general construction.

Figure 10 is a side view showing vertical position of the frame.

The machine is shown as consisting of two upright frames 10 composed of legs 11 arranged in opposed relation and connected by tie bolts 12.

55 A bed or platform 13 connects at the front

between the extended upper elements 14 of the frame, constituting a rigid stand.

Midway in the length of these upper elements, on their upper edges, are raised lugs 15 carrying pivots 16 engaged centrally in the side members of a rectangular frame 17 corresponding in dimensions to the top of the stand.

Attached to the rear member of the frame 17, by hinges 18, is an upper frame 19, identical with the lower frame 17 over which it is normally disposed in close contact.

Extending rigidly outward from the rear member of the upper frame 19, parallel and in register with its sides, are extension bars 20—20' having bearings 21—21' at their ends in which 70 are rotatably mounted shafts 22—22', reaching forwardly past the center of the frames and resting in bearings 23 attached to the frame sides.

One of these shafts, preferably on the right hand side of the machine, has fixed on its front end a bevel gear 24 meshed with a mating gear 25 rotatable on a stud 26 carried in a bracket attached to the upper frame 19, and operable by a hand-wheel 27, as best seen in Fig. 1.

80 The shaft 22 may be provided at its rear end, beyond the bearing 21, with a miter gear 28 meshed with a mating gear 29 fixed on a shaft 30 extending transversely between the rear ends of the bars 20—20'. In place of the gearing it will be apparent that a chain and sprockets may be used to connect these shafts.

85 The opposite end of the shaft 30 has fixed on it a miter gear 29' identical with but reversed to the gear 29, and meshed with a corresponding gear 28' fixed on the rear extending end of the shaft 22', thus coupling the shafts 22—22'.

The rear portions of both these shafts, extending contiguous to the bars 20—20', are screw-threaded and engaged thereon are blocks 30—30' 90 provided with tenons slidable in grooves 31—31' formed in the outer sides of the bars.

95 Fixed to extend between the adjacent sides of the blocks 30—30' is a bar 32 on which may be engaged weights 33 provided with slots to suit the bar, thus affording means of increasing or decreasing the effect of the blocks 30—30' as may be required. (See Fig. 2.)

100 In order to retain the frames 17—19 in a horizontal position on the stand, a latch 35, provided with an operating handle 36, is pivoted at 37 on the under frame 17, the latch having a catch 38 to engage a pin 39 set in the frame whereby the lower frame may be secured to the stand.

Another catch 40 on the latch member is adapted to engage with a similar pin 41 fixed in the upper frame 19, thus clamping the frames together and at the same time releasing them 5 both from the stand by action of the double latch.

It will now be apparent that, with the latch in the position shown in Fig. 1, both frames may be tilted on the stand carried pivot 16, raising 10 their front portions, their rear portions and extension bars being angularly depressed.

It will also be noted that when the double latch 35 is moved downwardly, the lower frame 17 will be held level on the stand and the upper frame 15 19 permitted to pivot on the hinges 18.

To adjust the counterbalancing weights, the hand-wheel 27 is turned, causing the shafts 22-22' to rotate in unison, due to their geared connections, and by reason of the removable 20 weights 33, a very considerable degree of counter-balancing is attainable and also such adjustment is retained by reason of the screw adjustment.

In Fig. 3, the shaft 22 is lengthened to extend 25 past the front edge of the upper frame 19 and provided with a hand-wheel 45 at its end, beyond the bearing 46 fixed on the upper frame 19.

A slide 47 is attached to the block 48, actuated 30 by the screw-threaded portion of the shaft 22, the slide being guided by a groove 49 in the upper frame and carries a downwardly offset detent bar 50 movable under a pin 51 set in the lower frame 17, thus providing means to 35 release the upper frame by actuation of the hand-wheel.

The block 48 may also be provided with removable weights 33', as shown.

The lower frame 17 also carries a pin 52 40 engageable by a hook latch 53, pivoted on a pin 54 set in the stand 14, thus affording means for securing the lower frame to the stand.

In Fig. 4, the slide bar 47 is lengthened and provided with a reversed detent bar 50' engageable 45 with a pin 51' set in the lower frame 17 nearer the pivot 16.

Figures 5 and 6 show a different form of stand 50 having an extended platform 56 and provided with rear extension bars, screw-shaft, bearings, hand-wheel and counter-weighting devices as previously described.

The stand sides have raised lugs 57 rearward of the center of their length, carrying pivot pins 58 on which are mounted the lower frame 55 17.

In Fig. 5 a double latch is shown of the same description as used in Fig. 1, and in Fig. 6 separate latches 59-60 are pivoted respectively on the stand and upper frame to engage pins 61-62 60 set in the lower frame.

A pair of parallel spaced fixed guides 63 are secured in upright position on the outer sides of the lower frame to receive between them slides 64 fixed centrally on the side members of the upper frame 19' and carried near the bottoms of these slides are rigid pins 65.

These fixed pins are contactable by angular arms 66 rigid with the extension bars 20 and upper frame, all of which are pivoted at 67 to the stand elements in Fig. 5 or, as shown in Fig. 6, to the lower frame at 67'.

It will now be seen that, in Fig. 5, upon tilting of the frames on the pivots 67 both will be raised angularly, if locked by the latch 35, and also the

upper frame raised from the lower frame of the latch will be moved downwardly.

Similar results are possible to obtain in the structure shown in Fig. 6.

In the modification shown in Fig. 7, a bar 70 is guided in the side edge of the upper frame 19, the bar carrying at its outer end a rod 71 to which may be attached one or more weights 72.

This bar may be manually moved and is provided with perforations 73 to receive a pin entering a corresponding opening in the frame to retain the weight in adjustment.

Fig. 8 shows a bar 75 carried by the upper frame and provided with a slot 76 in which is 85 90 95 98 99 100 105 110 115 120 125 130 135 140 145 149 150 155 160 165 170 175 180 185 190 195 200 205 210 - stand and lower frame, hinged connections between said frames, extension bars on said upper frame, a pair of screw shafts journalled in bearings carried by said upper frame and extension bars, geared connections between said shafts thereby to operate in unison, manual means carried by said upper frame to actuate said shafts, blocks threaded on said shafts, a bar connecting said blocks, and a plurality of weights independently disposable on said connecting bar. 5
7. In a stand for supporting an upper and lower frame, pivotal connections between said stand and lower frame, hinged connections between said frames, extension bars on said upper frame, a screw shaft journalled in bearings carried by said upper frame and bars respectively, counter-weighting blocks engaged on said shaft, slides actuated by said blocks, said slides being guided by the upper frame, detent bars carried by said slides, and pins set in the lower frame to engage said detent bars to lock said frames together. 15
8. In a stand for supporting an upper and lower frame, pivotal connections between said stand and lower frame, hinged connections between said frames, extension bars on said upper frame, said bars being slidable and provided with a plurality of spaced springs, counter-balancing weights carried by the outer ends of said bars, and detent pins engageable through the bar openings with the frame sides. 20
9. In a stand for supporting an upper and lower frame, pivotal connections between said stand and lower frame, means for detachably engaging the upper frame to the lower frame, guides on the sides of said stand, slides fixed on said upper frame to operate in said guides, a screw shaft pivoted at the rear of said upper frame, a counter-weight actuated by said shaft, 25 and means actuated by said shaft to engage said slides thereby to raise said upper frame from the lower frame. 30
10. In a stand for supporting an upper and lower frame, pivotal connections between said stand and lower frame, hinged connections between said frames, extension bars on said upper frame, said bars having elongated slots in their outer portions, a rod slidably guided at its ends in the slots to extend therebetween, weights 35 carried by said rod, a sprocket on the extending end of the rod, other sprockets mounted on one of said bars beyond the ends of the mentioned slot, and a chain trained over the last named sprocket, the upper run of said chain engaging the rod carried sprocket whereby the rod and weight may be adjustably positioned. 40
11. In a stand for supporting two frames, respectively upper and lower, said lower frame being pivotally attached midway its length to the stand, counter-weighted means for separating 45
- said frames, means for shifting said counter-weighted means, and means for detachably engaging said frames to swing as a unit on the pivotal attachment of the lower frame said means being also available to clamp the frames to said stand. 5
12. In a stand for a pair of frames, respectively upper and lower, pivotal connections between the sides of said stand and edges of the lower frame at its center, hinged connections between said frames at their end edges, extension bars on the upper frame, a screw shaft mounted in bearings carried by said upper frame and its extension, counterweights for said frame adjustable by said bar, a slidable detent on the upper frame, and a pin set in said stand engageable by said detent. 85
13. In a stand for supporting two frames, respectively upper and lower, pivots attaching the lower frame to said stand, hinges connecting the frame, a counterweight for said frames having screw adjustment, a detent slidable on the upper of said frames, a pin set in the lower frame to engage said detent, a second pin in the lower frame, and a catch pivoted on said stand 90 to engage said second pin. 95
14. In a stand for supporting two frames, respectively upper and lower, said lower frame being pivotally attached to the stand, vertical guides on the sides of said stand, slides fixed on the upper frame to operate in said guides, pins fixed in said slides, and screw actuated angular arms slidable on said stand to engage said pins thereby to raise the upper frame in a plane parallel to the lower frame. 100
15. In a stand for supporting two frames, respectively upper and lower, said lower frame being pivotally attached to the stand, vertical guides on the sides of said stand, slides fixed on the upper frame to operate in said guides, pins fixed in said slides, screw actuated angular arms slidable on said stand to engage said pins thereby to raise the upper frame in a plane parallel to the lower frame, registering pins set in the edges of said upper frame and said stand, and unitary 110 catches pivoted to the sides of the lower frame to selectively engage the pins in the upper frame or the pins in said stand. 115
16. In a stand for supporting two frames, respectively upper and lower, said lower frame being pivotally attached to the stand, vertical guides on the sides of said stand, slides fixed on the upper frame to operate in said guides, pins fixed in said slides, screw actuated angular arms 120 slidable horizontally at the sides of said lower frame to engage the pins carried by said slides, means for clamping said frames together, and means to clamp the lower frame to said stand. 125

HARRY C. JONES. 135
